UNITED STATES PATENT OFFICE.

JOSEF BREJCHA, OF STRASBURG-NEUDORF, GERMANY.

APPARATUS FOR RINSING THE CORES OF ROCK-DRILLING MACHINES.

SPECIFICATION forming part of Letters Patent No. 766,588, dated August 2, 1904.

Application filed July 15, 1902. Serial No. 115,718. (No model.)

To all whom it may concern:

Be it known that I, JOSEF BREJCHA, a subject of the Emperor of Germany, residing at Strasburg - Neudorf, Alsace - Lorraine, Germany, have invented certain new and useful Improvements in Apparatus for Rinsing the Cores of Rock-Drilling Machines, of which the following is a specification.

My invention relates to an apparatus for rinsing and washing the cores of rock-drilling machines in the course of the boring. The force-water comes from without through the cutter to the drill-stock and presses out the bore-hole grit with the cores, preventing through it the jamming of the cutter. The water operates in course for the movement of the cores, and the drill-stock is perfectly round and is let open in its rear end.

A form of construction of the object of the invention is illustrated by way of example in the accompanying drawings, in which—

Figure 1 is a section through the apparatus. Fig. 2 is a front elevation of it with a section through the rear end of the drilling-machine. A case *b* is seated on the hollow drill-stock *c*, closed water-tight by two rings *g* *f*, of caoutchouc or other material, and possesses a water-tube *a*. The ring *g* secures the force-water entering through the pipe *a* from running out of the case *b*, and the ring *f* is pressed to the rock in such a manner that the coming in of the water into the bore-hole is done without loss. The cutter *i* has a larger diameter than the drill-stock and is supplied with chamfers *k*, through which the water can come to the interior of the drill-stock. The case *b* is braced by an arm *d*, which can be removed in a tube *e*, fixed on the frame of the machine by means of a worm with a nut *p*.

The water gets through the water-pipe *l* 40 and the tube *a* to the case *b*, comes through the ring *f* between the drill-stock and the rock through the chamfers *k* of the cutter *i* to the interior of the hollow drill-stock *c*, and presses the cores *m*, with the bore-hole grit, through 45 the drill-stock, open in its rear end, preventing through it the jamming of the cutter.

Having thus described my invention, what I claim, and desire to secure by Letters Patent, is—

1. In a rock-drill, the combination with a tubular drill-stock, a casing carried by the drill-stock and bearing against the surface to be drilled and means interposed between said casing and the drill-frame for moving said casing forward, said means comprising a rearwardly-extending arm carried by the casing, a socket on the drill-frame for receiving said arm and means carried by said arm for moving the same forward, substantially as described. 50

2. In a rock-drill, the combination with a tubular drill-stock, a casing carried by the drill-stock and bearing against the surface to be drilled and means interposed between said casing and the drill-frame for moving said casing forward, said means comprising a rearwardly-extending arm carried by the casing, a socket on the drill-frame for receiving said arm and a nut threaded on said arm for moving the same forward, substantially as described. 65 70

In witness whereof I have hereunto set my hand in presence of two witnesses.

JOSEF BREJCHA.
